UNITED STATES PATENT OFFICE.

EVERMONT BLEVINS MINER, OF PORTLAND, OREGON.

TUBE BEADING OR FLANGING MACHINE.

1,420,383.

Specification of Letters Patent. Patented June 20, 1922.

Application filed January 24, 1921. Serial No. 439,631.

To all whom it may concern:

Be it known that I, EVERMONT BLEVINS MINER, a citizen of the United States, and a resident of Portland, in the county of 5 Multnomah and State of Oregon, have invented certain new and useful Improvements in Tube Beading or Flanging Machines, of which the following is a specification.

10 The present invention relates to tube beading or flanging machines, especially adapted for use with boiler tubes.

The object of the invention is to provide a machine of this character which is adapted to provide the requisite bead or flange at the end of the tube of a boiler when the same is in position in the boiler, which is of simple and durable construction, reliable in operation, and easy and inexpensive to 20 manufacture and which enables the beading of the tube to be effectively carried out with a minimum expenditure of time, labor and skill.

Other objects and advantages of the invention reside in certain novel features of construction, combination and arrangement of parts which will be hereinafter more fully described and particularly pointed out in the appended claims, reference being 25 had to the accompanying drawings forming part of this specification, and in which:

Figure 1 is a view in longitudinal section, parts being shown in elevation for the sake of illustration;

30 Figure 2 is a view in elevation, showing the preferred embodiment of the invention;

Figure 3 is a transverse sectional view on line 3—3 of Figure 1;

Figure 4 is a sectional view on line 4—4 35 of Figure 1;

Figure 5 is a transverse sectional view on line 5—5 of Figure 1, showing the parts in non-gripping position;

Figure 6 is a similar view, showing the 40 parts in gripping position;

Figure 7 is a transverse sectional view on line 7—7 of Figure 1;

Figure 8 is a transverse vertical sectional view on line 8—8 of Figure 1.

50 Referring to the drawings wherein for the sake of illustration is shown the preferred embodiment of the invention, the numeral 10 designates a rotatable shaft.

Gripping means is arranged on the shaft 55 and comprises a mandrel 11 divided longi-

tudinally and thus consisting of two sections, designated at 12 and 13. The sections of the mandrel are retained on the shaft 10 against radial displacement by means of collars 14 and 14^a integrally formed with the section 12 at the opposite ends thereof and loosely embracing the shaft 10 and collars 15 and 15^a integrally formed with the section 13 at the opposite ends thereof and also loosely embracing the shaft 10, as 60 clearly shown in Figure 1. These collars while permitting expansion of the sections of the mandrel and thus allowing radial movement within certain limits prevent such radial displacement as would disassociate the sections of the mandrel from the shaft 10.

Means is provided for preventing longitudinal displacement of the sections of the mandrel and comprises an end plate 16 75 secured by nuts 17 to the one end of the shaft 10 and engageable with the portion of the section 12 of the mandrel, and an annular shoulder 18, preferably integrally formed with the shaft at a point adjacent 80 the opposite end of the mandrel and engageable with a portion of the section 13 thereof.

The sections 12 and 13 of the mandrel are adapted to be expanded into gripping 85 engagement with the wall or flue or tube being beaded, and for this purpose expanding means is provided which consists of expanders 19, 20, 21 and 22, preferably in the form of integral eccentric lugs carried by 90 the shaft 10, and engageable with inwardly extending coacting lugs 23, 24, 25 and 26 formed on the sections 12 and 13 of the mandrel. The eccentric lugs of the shaft, the coacting lugs of the mandrel, the collars which embrace the shaft to prevent radial displacement, and the collar and end plate which prevent longitudinal displacement are organized as clearly shown in Figure 1, so that one does not interfere with 100 the function of the other but rather furthers this function as they slidably abut each other and thus constrain each other to the proper field of action. Moreover, these elements transmit the retaining action of the plate 16 and the collar 18 to the opposite sections of the mandrel.

A plurality of beading or flanging rollers 30 are arranged on the shaft at one end of the mandrel. These beading rollers are 110

rotatably mounted on inclined pintles 31 which are journaled in a cage consisting of inner and outer concentric rings 32 and 33, respectively. Each beading or flanging 5 roller is tapered and comprises an inner frusto-conical portion 30^a, an outer frusto-conical portion 30^b and a concave or reduced portion 30^c formed by providing an annular groove in the roller intermediate 10 the portions 30^a and 30^b.

A working head 35 is rotatably and slidably arranged on the shaft 10 adjacent the beading rollers and has a working face 35^a upon which the rollers operatively bear. 15 The working face 35^a is formed by a flange 35^b extending laterally from the body portion of the working head, and this working face presents a relatively large smooth and inclined surface which completely supports 20 the beading rollers as the frusto-conical portions 30^a and 30^b both roll on the working face. Handles 36 extending laterally from the body portion of the working head and facilitate its rotation. A thrust collar 37 25 having a ball race 38 therein in which ball bearings 39 are operatively arranged, is also arranged upon the shaft 10 immediate to and with its ball bearings 39 engaging the working head, as shown in Figure 1.

30 Feeding mechanism is provided and consists of a feeding block 40 having threading engagement with the threaded portion 10^a of the shaft 10 and bearing against the thrust collar 37 and thus serving in conjunction 35 with the thrust collar to advance the working head and the abutting rollers during the heading operation. Handles 41 project laterally from the block 40 of the feeding mechanism and facilitate turning of the 40 block in feeding of the rollers.

In operation the mandrel 11 is inserted in the tube to be beaded and the squared portion 29 of the shaft 10 is engaged by a suitable tool and rotated so that the eccentric 45 lugs of the shaft cooperate with the lugs of the sections of the mandrel and expand these sections into gripping engagement with the wall of the tube. The handles 41 of the feeding block are then grasped and the feeding block is turned to advance the working head and the beading rollers until the beading rollers engage the tube. The handles 36 of the working head are then utilized to turn the working head, and this turning of the 50 working head causes the beading rollers to operate upon or swage the metal of the tube to form the bead or flange. During this operation the feeding mechanism is utilized to advance the working head as the formation 55 of the bead progresses. After the beading operation has been completed the shaft 11 is reversely rotated to permit the sections of the mandrel to collapse out of gripping engagement with the wall of the tube and

thus allow its ready withdrawal therefrom. 65

I claim:

1. In a device of the character described, a rotatable shaft, a mandrel arranged on said shaft consisting of sections, means for retaining said sections against radial displacement while permitting expansive movement, means for retaining said sections against longitudinal displacement, means operable by said shaft for expanding said sections, beading rollers arranged on said shaft adjacent said mandrel, a cage for said rollers, a working head arranged on said shaft and having a working face against which said rollers bear, means for rotating said working head, feeding mechanism comprising a rotatable block threaded on said shaft and means for rotating said block, and a thrust collar arranged on said shaft between said rotating block and said working head. 75

15 2. In a device of the character described, a shaft, a mandrel on said shaft consisting of sections, means for expanding said sections comprising eccentric lugs carried upon said shaft and cooperable with said sections, beading rollers arranged upon said shaft, a working head for said rollers arranged upon said shaft and feeding mechanism for advancing said rollers and working head during 80 said feeding operation. 90

25 3. In a device of the character described, a shaft, a mandrel on said shaft consisting of sections, means for limiting the radial movement of said sections, including collars carried by the sections and embracing the shaft, means for preventing longitudinal displacement of said sections, means for expanding said sections comprising eccentric lugs carried by the shaft and cooperable with said sections and beading rollers arranged upon 100 said shaft adjacent said mandrel. 105

30 4. In a device of the character described, a shaft, a mandrel associated with said shaft, beading rollers operating on said shaft and each including an inner frusto-conical portion, an outer frusto-conical portion and an intermediate reduced portion between said frusto-conical portion, a cage for said rollers comprising concentric rings, pintles journaled in said rings and rotatably supporting said rollers, a working head arranged upon said shaft and including a body portion and a laterally extending flange, the laterally extending flange presenting a working face having a relatively large smooth area and 115 being inclined to completely engage the lateral surfaces presented by both of the frusto-conical portions of each of the beading rollers, means for rotating said working head, and feeding mechanism cooperating 120 with said shaft for advancing said working head of the beading rollers. 125
